UNITED STATES PATENT OFFICE

ELDRIDGE R. F. JOHNSON, OF MOORESTOWN, AND SELDEN T. WILLIAMS, OF WOODBURY, NEW JERSEY, ASSIGNEES TO VICTOR TALKING MACHINE COMPANY, A CORPORATION OF NEW JERSEY

COMBINED TONE ARM AND ELECTRICAL PICK-UP

Application filed April 21, 1926. Serial No. 103,635.

This invention relates to talking machines, and more particularly to talking machines adapted to reproduce a record both mechanically and electrically.

5 One object of the invention is to provide a talking machine with means whereby a record may be reproduced either mechanically or electrically at the option of the operator.

Another object is to mount the mechanical 10 and electrical reproducing mechanisms on a common supporting member which is adapted to form a tone arm for the mechanical reproducing mechanism.

Another object is to mount the reproducing 15 mechanisms so that they swing in the same path of movement relative to the record.

A further object is to mount the reproducing mechanisms so that their respective tracking members have the same limiting positions.

Another object is to mount the reproducing mechanisms so that the respective tracking members occupy substantially the same playing position.

25 A further object is to provide means whereby both reproducing mechanisms may be supported on a single swinging member so that their respective styli will engage the record groove at the same point.

30 One embodiment of the invention has been illustrated in the accompanying drawings, but it is to be expressly understood that these drawings are not to be construed as a definition of the invention, reference being had to the appended claims for that purpose.

In the drawings—

Fig. 1 is a view showing one embodiment of the invention;

Fig. 2 is a plan view of Fig. 1;

40 Fig. 3 is a detail view in section showing the carrying arm; and

Fig. 4 is a detail view in section showing another form of carrying arm.

45 Referring to the drawings wherein like reference numerals indicate like parts, 1 indicates the record support of a talking machine of any suitable type, having any suitable record 2 thereon. Said talking machine is provided with a tone arm 3 of any suitable type, shown as pivoted about a verti-

cal axis 4, and having any suitable sound box 5 pivotally secured thereon in any suitable way, preferably by means of the usual gooseneck 6. The sound box 5 carries any suitable stylus 7 for engagement with the record trace, and is adapted to occupy either the non-playing position, shown in full lines in the drawings, or the playing position, shown in dotted lines, by reason of the pivotal mounting afforded by said gooseneck 6.

55 In conformity with the present invention, means are provided for pivotally mounting an electrical pick-up device, of any suitable type on the tone arm 3, preferably in such a manner that its stylus will engage the record

groove at substantially the same point as the stylus 7 of the sound box 5. An electrical pick-up device 8, having a stylus 9 for engagement with the record trace, is adapted to transmit the mechanical vibrations received from the sound groove electrically to any suitable apparatus for reproducing sound. In the form shown, the pick-up device 8 is supported on a carrying arm 10 in

50 any suitable manner, as by means of an annular projection 11 on one end of said carrying arm which engages the neck of said pick-up device, and suitable means are provided for pivoting said carrying arm to the tone arm. As shown, a bracket 12 is suitably secured to the tone arm, as by means of screws 13 said bracket having a centrally arranged cylindrical projection 14 which engages an opening 15 in the other end of the carrying arm 10. Said projection is prefer-

55 ably internally threaded to receive a screw 16 which holds the carrying arm in position. The pick-up device 8 may thus be swung by means of the carrying arm 10 from the playing position, shown in full lines in the drawings, to the non-playing position, shown in dotted lines, and the bracket 12 is preferably provided with a suitable stop member 17 which limits the motion of carrying arm 10 in both directions about its pivotal axis.

90 The sound box gooseneck 6 and the carrying arm 10 are pivoted about axes angularly related to the longitudinal direction of the tone arm, and said axes are preferably later-

ally spaced so that, when the pick-up device is in playing position, the stylus 9 will occupy substantially the same position as the stylus 7 of the sound box when the latter is in playing position. The two styli thus alternatively engage the sound groove of the record at substantially the same point at every position of the tone arm and follow the same arc of travel about the pivot 4 while the record is being played.

13 The pick-up device may be electrically connected with suitable reproducing apparatus by means of the leads 18. Preferably the carrying arm 10 is provided at one end with an opening 19 which is disposed centrally of the annular projection 11 and extends therethrough to the pick-up device 8, and adjacent its other end with a similar opening 20, the two openings being connected by a 15 groove 21 on the inner face of said carrying arm. The leads 18 may be conducted through the opening 19 and housed in groove 21, being then conducted through opening 20 to a suitable conduit 22 which is preferably secured to the lower side of the tone arm 3 as by means of brackets 23 and screws 24. As shown, one of the brackets 23 may be formed as a part of a downwardly projecting stop member 25 provided for operating 20 the trip mechanism of the talking machine.

Fig. 4 illustrates another form of carrying arm which may be employed to support the pick-up device 8, wherein the leads 18 may be permanently connected to suitable 35 contact members which are adapted to engage corresponding contacts on said pick-up device when the latter is placed in position. As shown in the drawing, the annular projection 11 is closed at its inner end and has a lateral opening 19 adjacent the latter which communicates with the groove 21. The bottom of the recess within the annular projection 11 is preferably insulated as by means of a disc 26 of any suitable material. The 40 leads 18 may be conducted through the groove 21 and opening 19 into said recess, where they may be suitably connected as by means of soldering to suitable contact members described hereinafter.

50 In the form shown, a plug 27 of suitable insulating material is inserted in the recess and secured therein as by means of a screw 28. The inner face or base of said plug preferably rests against the insulating disc 26, and is provided with suitable grooves in which the leads may be housed. Extending from these grooves are suitable openings 29 cut through the plug to the outer face of the latter. Bushings 30, preferably of brass, are 55 fitted in the openings 29, and are provided with inwardly extending shoulders 31 adjacent their inner ends, leaving central openings through which contact pins 32 are adapted to slide. The pins are provided adjacent 60 their outer ends with shoulders 33 fitting

within the bushings 30, and resilient means such as coil springs 34 are interposed between shoulders 31 of the bushings and 33 of the contact pins. These springs normally urge said pins outwardly, and the latter are prevented from disengaging from the bushings 30 by any suitable means such as washers 35 suitably secured to the inner end of the pins.

70 A plug 36, suitably secured to the neck of the pick-up device 8, as by a screw 37, is adapted to be inserted into the annular projection 11, said pick-up device being suitably retained on said projection 11 as by the engagement of said neck therewith. Said plug 75 36 carries suitable contact members 38 adapted to engage the contact pins 32, and owing to their spring mountings, said pins 32 are adapted at all times to assure a good contact with said pins 38. The electric circuit of said 80 85 pick-up device is therefore completed automatically by merely mounting said pick-up device on its carrying arm.

It will be seen that a talking machine constructed according to the invention may be 90 employed for reproducing a record, either mechanically by means of the sound box, or electrically by means of the pick-up device, at the option of the operator. By mounting the reproducing mechanisms in the manner disclosed, both styli have the same limit positions in their path of movement, which is of importance in case it is desired to employ repeating or stylus restoring mechanism. Moreover, since both styli engage a record at 95 the same point, the stop mechanism of the machine will be operated by the trip member 25 at the same point in the playing of the record when either stylus is in use.

100 Furthermore, by so mounting the two reproducing mechanisms on a single swinging member, the necessity for providing separate 105 mountings is removed. The use of one swinging arm not only conserves space within the upper compartment of the machine, and thus minimizes any interference with the ready 110 operation of the latter, but also avoids multiplicity of parts and increases the economy and simplicity of construction. Moreover, 115 the two tracking members are so supported that they follow exactly the same arc of travel relative to the record, and the same efficiency of reproduction is obtained when either mechanism is in use.

120 While only two embodiments of the invention have been illustrated in the drawings, it will be apparent that the invention is susceptible of a variety of expressions and that changes may be made in the details of construction and arrangement of parts without departing from the spirit of the invention. Reference is therefore to be had to the appended claims for a definition of the limits 125 of the invention.

What is claimed is:

1. In a talking machine including a tone arm, reproducing means including a stylus pivotally connected to the tone arm, and means including a stylus pivotally connected to the tone arm for transmitting sound vibrations electrically, said styli being connected to said tone arm so that they occupy substantially the same playing position. 5
- 10 2. In a talking machine, in combination with a tone arm having a sound box and stylus pivotally mounted thereon, an electrical transmitting device pivotally mounted on said tone arm about an axis angularly related to the pivotal axis of said sound box and having a stylus adapted to engage a record when said sound box is in non-playing position, said styli having the same playing position. 15
- 15 3. In a talking machine, in combination, a tone arm, sound reproducing means pivotally mounted thereon, and means pivotally mounted on said tone arm for reproducing sound electrically, each of said means having a stylus and being mounted so that said styli travel in the same path of movement. 20
- 20 4. In a talking machine, in combination, a tone arm, a sound box pivotally mounted on the tone arm and having a stylus, an electrical pick-up device having a stylus, and means for pivoting said pick-up device on said tone arm, said sound box and pick-up device being so mounted on said tone arm that said styli are adapted to travel in the same 25 path of movement. 25
- 25 5. In a talking machine, a tone arm, a sound box pivotally supported thereon and having a stylus for engagement with a record, an arm pivotally secured to said tone arm, an electrical transmitting device on said arm, said device having a stylus for engagement with a record, said transmitting device and sound box being so mounted that their respective styli engage the sound groove at 30 the same point when in playing position. 30
- 30 6. In a talking machine, a tone arm swinging about a vertical axis, a sound reproducing mechanism pivoted to said tone arm about a horizontal axis, and a second sound reproducing mechanism pivoted to said tone arm about a horizontal axis independently of said first-named mechanism, said axes being angularly related, said mechanisms having styli which engage the record groove at 35 the same point. 35
- 35 7. In a talking machine, a swinging tone arm, a sound box pivoted on said arm about an axis transverse to its length, and a magnetic pick-up device pivoted to said arm about an axis transverse thereto, said axes being laterally spaced so that said sound box and pick-up device have the same playing position. 40
- 40 8. In a talking machine, a swinging tone arm, a sound box pivotally mounted thereon, 45
- 45 a bracket on said tone arm, a member pivoted on said bracket, and a magnetic pick-up device on said member, said sound box and pick-up device having styli and being mounted so that said styli engage a record groove at the same point when in playing position. 50
- 50 9. In a talking machine, a swinging tone arm, a sound box pivotally mounted thereon and provided with a stylus, a carrying arm, a magnetic pick-up device on said carrying arm and provided with a stylus, and means for pivoting said carrying arm on said tone arm whereby the stylus of said pick-up device occupies the same playing position as the stylus of said sound box. 55
- 55 10. In a talking machine, a swinging tone arm, a sound box pivotally mounted thereon, a carrying arm, an electrical pick-up device on said carrying arm, and means for pivoting the latter on said tone arm, said carrying arm being provided on its inner face with a longitudinally extending groove for housing a pair of electrical leads. 60
- 60 11. In a talking machine including a tone arm, reproducing means pivotally connected to the tone arm and including a stylus, and means pivotally connected to said tone arm and including a stylus for transmitting sound vibrations electrically, said styli having the same limiting playing positions. 65
- 65 12. In a talking machine, a tone arm, sound reproducing means pivotally mounted thereon, and means pivotally mounted on said tone arm for reproducing a record electrically, each of said means having a stylus and being pivoted about axes which are so related that said styli have the same limiting playing positions. 70
- 70 13. In a talking machine, a swinging tone arm, a sound box pivotally mounted thereon and having a stylus, and an electrical pick-up device pivotally mounted on said tone arm and having a stylus, said sound box and pick-up device being so mounted that said styli are adapted to follow the same path of travel relative to the record and have the same limiting positions. 75
- 75 14. In a talking machine, a swinging tone arm, a sound box pivotally mounted thereon and having a stylus, an electrical pick-up device having a stylus, and means for pivotally mounting said pick-up device on said tone arm, the pivotal axes of said sound box and pick-up device being so related that said styli are adapted to occupy the same playing position when said tone arm is swung to its limiting position. 80
- 80 In testimony whereof we have signed this specification.
